UNITED STATES PATENT OFFICE.

LUCIAN ROSENWALD, OF KANSAS CITY, MISSOURI.

FOLDING BOX.

1,168,566.

Specification of Letters Patent. Patented Jan. 18, 1916.

Application filed July 27, 1914. Serial No. 853,262.

To all whom it may concern:

Be it known that I, LUCIAN ROSENWALD, a citizen of the United States, residing at Kansas City, in the county of Jackson and State of Missouri, have invented a certain new and useful Improvement in Folding Boxes, of which the following is a specification.

My invention relates to improvements in folding boxes.

My invention is particularly adapted to be applied to boxes used for fruit or berries, but it may also be used for many other purposes.

15 The object of my invention is to provide a box which is of novel construction, and which may be cheaply made, is strong and durable, and which may be readily collapsed to flat form.

20 The novel features of my invention are hereinafter fully described and claimed.

In the accompanying drawing, which illustrates the preferred embodiment of my invention, Figure 1 is a perspective view, 25 partly broken away, of my improved box, shown set up for use. Fig. 2 is a vertical longitudinal sectional view of the same. Fig. 3 is a cross section of the same. Fig. 4 is a plan view of the body shown collapsed. Fig. 5 is an edge view of the body shown collapsed. Fig. 6 is a plan view of 30 the blank from which the body is made.

Similar reference characters designate similar parts in the different views.

35 In the following description and claims, the term "sides" includes the ends of the box.

1, 2, 3 and 4 designate the sides of the box flexibly connected with each other at 40 the corners of the body of the box by flexible joints 5. The side 1 is composed, preferably of two members 6 and 7 which overlap and are secured to each other, and which embrace between them a flap 8 flexibly connected to one longitudinal edge of the bottom 9, the opposite edge of which is flexibly connected to the lower edge of the side 2. The sides 3 and 4 are respectively provided with vertical flexible joints 10, 45 each disposed intermediate of the adjacent corners of the body. The free end edges of the bottom 9 have respectively flexibly connected to them two flaps 11 which, when the body is extended, as shown in Figs. 1, 50 2 and 3, are adapted to be extended up-

wardly outside of the body and to be respectively folded over the upper edges of the sides 3 and 4, and then extended downwardly in the body to the bottom 9 and then bent inwardly and extended along the bottom to a position in which the flaps 11 will overlap each other, as shown in Fig. 1. The flaps 11 may be provided respectively with transverse joints 12, 13 and 14, formed by creasing or scoring, and respectively disposed where the flaps are connected to the bottom 9; where the flaps are folded over the upper edges of the sides 3 and 4; and where the flaps are bent inwardly at the bottom 9. The bottom 9 is provided with a flexible joint 15 which, when the body is either extended or folded, is in alinement with, that is, in the plane of the flexible joints 10 in the ends 3 and 4. The flaps 11 are each provided with a longitudinal flexible joint 16, which is disposed in alinement with the joints 10 and 15. The provision of the joints 5 at the corners of the body, the flexible connection between the longitudinal edges of the bottom and the sides 1 and 2, the joints 10, 15 and 16, and the joints 13 permit the box to be folded to the flat form shown in Figs. 4 and 5.

In forming the box from the blank shown in Fig. 6, the flap 8 and side 2 are first bent to a vertical position at their connection with the bottom 9. The sides 3 and 4, carrying the side portions 6 and 7, which form the side 1, are then swung on the joints 5 at right angles and adjacent to the ends of the bottom 9. The portions 6 and 7 are then swung on the joints 5, which connect them to the sides 4 and 3, to positions parallel with the side 2 and at opposite sides of the flap 8, said portions 6 and 7 being then secured in any suitable manner, as by stapping or cementing, to the flap 8 and to each other. The flaps 11 are then folded upwardly along the joints 12, and then folded along the joints 13 over the upper edges of the sides 3 and 4, and then extended vertically to the bottom 9 along the inner sides of the body, and then bent inwardly along the joints 14, so as to rest upon the bottom 9. Preferably the flaps 11 have sufficient length when so positioned to overlap each other, as shown in Figs. 1 and 2. The flaps 11 serve to strengthen the bottom 9 and to prevent its being bent along the joint 15. They also serve to strengthen the sides 3 and 4 and to

prevent bending of said sides along the joints 10. By having the flaps 11 overlap the upper edges of the sides 3 and 4, the free edges of the bottom 9 are firmly suspended.

5 If desired, a flat removable bottom 17 may be fitted within the body, as shown in Figs. 1, 2 and 3, and disposed upon the flaps 11, thereby retaining said flaps securely in 10 their operative positions, as well as greatly strengthening the box and holding it in the set up or extended form.

The body may be provided with suitable inlets for air, as, for example, by providing 15 notches 18 in the upper edges of the sides 1 and 2, which permit air to enter the box when it is mounted in a pile with others.

In assembling the box for storage or 20 shipment empty, the removable bottom 17 is taken out, after which the flaps 11 are extended horizontally at opposite ends of the bottom 9, after which the box may be collapsed to flat form by folding the sides 3 and 4 along the joints 10, the corner joints 5 permitting 25 this, and by folding the bottom 9 and flaps 11 along the joints 15 and 16, after which the flaps may each be folded onto itself along the joint 13. The box will now 30 be in the collapsed flat form shown in Figs. 4 and 5.

The box, with the exception of the removable bottom 17, may be made from a single strip of material, such as card board or sheet wood, as shown in Fig. 6. When so made, 35 longitudinal slits 19, in alignment with the flexible connection between the bottom 9 and the side 2, are provided in the strip from the ends of the portions 6 and 7 respectively to the flexible joints 5 respectively at opposite 40 ends of the side 2. The flaps are thus separated from the side portions 7 and 3 and 4 and 6 respectively. By means of this construction, very little waste of material is required and such permanent fastenings as 45 may be needed can be effected in a single operation.

I do not limit my invention to the structure shown and described, as modifications, 50 within the scope of the appended claims, may be made without departing from the spirit of my invention.

Having thus described my invention, what I claim and desire to secure by Letters Patent, is:—

55 1. A folding box comprising a body having sides flexibly connected with each other, two opposite sides having each intermediate of the adjacent corners a vertical flexible joint, a bottom flexibly connected at opposite edges with two sides and having a flexible joint disposed in alignment with said vertical flexible joints, and two flaps respectively flexibly connected to opposite edges of said bottom and adapted to be extended upwardly and folded over the upper

edges of said sides provided with said vertical joints.

2. A folding box comprising a body having sides flexibly connected with each other, two opposite sides having each intermediate 70 of the adjacent corners a vertical flexible joint, a bottom flexibly connected at opposite edges with two other sides respectively and having a flexible joint extending between opposite edges in alignment with said 75 vertical joints, and two flaps respectively flexibly connected to opposite edges of said bottom and adapted to be extended upwardly outside of the body and folded over the upper edges respectively of said sides 80 having said vertical joints, the ends of said flaps being adapted to be bent inwardly adjacent to the lower edges of said sides having the vertical flexible joints and to rest upon the upper side of said bottom. 85

3. A folding box comprising a body having sides flexibly connected with each other, two opposite sides having each intermediate 90 of the adjacent corners a flexible vertical joint, a bottom flexibly connected at opposite edges respectively with two other opposing sides and having a flexible joint extending between two other opposite edges in alignment with said vertical flexible joints, and two flaps respectively flexibly connected 95 to the edges at which terminates the flexible joint of the bottom, said flaps having respectively flexible joints in alignment with the flexible joint of the bottom, and being adapted to be extended upwardly and folded over 100 the upper edges of the sides having said vertical joints.

4. A folding box comprising a body having sides flexibly connected with each other, two opposite sides having each a vertical 105 flexible joint intermediate of the adjacent corners, a bottom having two opposite edges respectively flexibly connected with two other sides and having a flexible joint extending between two other edges in alignment with said vertical joints, two flaps respectively flexibly connected with opposite edges of said bottom and adapted to be extended upwardly and to be folded over the upper edges respectively of the sides having 110 said vertical joints, and a removable bottom member adapted to be fitted in said body and to rest upon said bottom. 115

5. A folding box comprising a body having sides flexibly connected with each other, two opposite sides having each a vertical 120 flexible joint intermediate of the adjacent corners, a bottom having two opposite edges respectively flexibly connected to two other opposing sides and having extending between opposite edges a flexible joint in alignment with said vertical joints, and two flaps respectively flexibly connected with the edges of the bottom at which terminates the joint thereof, and adapted to be extended 125 130

upwardly outside the body and to be folded respectively over the upper edges of the sides having said joints and to be extended downwardly to the bottom and then bent inwardly so as to rest upon the bottom, and in the last named position overlapping each other.

Copies of this patent may be obtained for five cents each, by addressing the "Commissioner of Patents, Washington, D. C."

In testimony whereof I have signed my name to this specification in presence of two subscribing witnesses.

LUCIAN ROSENWALD.
